GORHAM MANUFACTURING CO.

ASSIGNEES OF

GEORGE WILKINSON'S

"Bridal," Design for Handles of Forks, Spoons, and other Table Ware.

Witnesses,
J. G. Lawton / Inventor. Geo. Wilkinson
Isaac A. Brunelle.

United States Patent Office.

GEORGE WILKINSON, OF PROVIDENCE, RHODE ISLAND, ASSIGNOR TO
GORHAM MANUFACTURING COMPANY, OF SAME PLACE.

Design No. 3,110, dated July 14, 1868.

DESIGN FOR A FORK OR SPOON-HANDLE CALLED "BRIDAL."

The Schedule referred to in these Letters Patent and making part of the same.

TO ALL WHOM IT MAY CONCERN:

Be it known that I, GEORGE WILKINSON, of the city and county of Providence, and State of Rhode Island, have originated a new Design for Articles of Silver and other Metals and Plated Ware, of which the following is a full, clear, and exact description, reference being had to the accompanying specimens or drawings, making part of this specification, that is to say, a design called the "Bridal," for the handles of forks, spoons, and other table-ware and implements.

The said handle, as represented in said drawings, has a rounded stem, E, slightly flattened where it joins the spoon or fork, &c.

The blade F has an oval centre, surrounded with an oval bead, f, with a margin which expands into scrolls f f above and below.

Near the junction of the stem E with the blade F is an ornament of ribbon, D, entwining the stem in repeated crossings and folds.

The handle is surmounted with a pair of doves, A, from which the design derives its name.

Claim.

I claim the design for the handles of forks, spoons, &c., substantially as herein represented and described.

GEO. WILKINSON.

Witnesses:

J. F. P. LAWTON,
ISAAC A. BROWNELL.
